[57] CLAIM

The ornamental design for a snack tray, as shown and
described.

DESCRIPTION

FIG. 1 is a perspective view of the snack tray showing
a first embodiment of my new design;

FIG. 2 is a top plan view of the first embodiment of the
snack tray;

FIG. 3 is a bottom plan view of the first embodiment of
the snack tray;

FIG. 4 is a front elevational view of the first embodiment
of the snack tray;

FIG. 5 is a side elevational view of the first embodiment
of the snack tray;

FIG. 6 is a perspective view of the snack tray showing
a second embodiment of my new design;

FIG. 7 is a top plan view of the second embodiment of
the snack tray;

FIG. 8 is a bottom plan view of the second embodiment
of the snack tray;

FIG. 9 is a front elevational view of the second embodiment
of the snack tray; and

FIG. 10 is a side elevational view of the second embodiment
of the snack tray.
